UNITED STATES PATENT OFFICE.

ARTHUR HUGO MÜLLER, OF BLANKENESE, NEAR HAMBURG, GERMANY.

PLANT FOR TOWING VESSELS ON INLAND WATERWAYS.

Application filed February 9, 1926, Serial No. 87,162, and in Germany in part May 28, 1925, and in part November 30, 1925.

For many years repeated attempts have been made to provide for towing vessels on inland water ways by driving devices which move along a stationary path or track, for instance a rail-way, a chain or a cable arranged either on the bank or on the water-bed or in the air above the water-way. The arrangement of the track on the bank or in the water presents well known drawbacks, which preclude the general introduction of these systems of towage. These drawbacks are not met with where the track is mounted in the air above the water-way, but the objection is found in the high cost. In the present state of the art it is possible to construct such a track above the water to form a rigid structure similar to the Elberfeld suspension track or electric overhead railway which would be technically satisfactory, but it is certain that such an installation for towing vessels, particularly on account of the necessary spans of 100 to 300 metres, would be far too expensive.

In prior attempts to solve this problem it has been generally proposed to employ cable- or chainlike tracks. The construction of such chain-like or flexible tracks is a difficult problem, particularly in the case where the track has not merely to take up the pull of the vessel longitudinally and transversally, but also the weight of the tug or trolley. Due to the influence of the weight and the vertical component of the towing effort a large sag of the chain- or rope-like track is produced, impairing the efficiency and causing detrimental swaying or rocking and premature wear and tear and other drawbacks.

The installation of the invention represents a solution of the problem, constituting a happy combination of the rigid principle of electric suspended railways with the chain- or cable-track principle.

A track, along which the tug or trolley moves, is suspended and stiffened in the vertical plane by a suspension structure spanned between fixed points but unstiffened in transverse direction. This supporting structure may be subjected to the action of lateral forces to undergo laterally swinging movements and distortions without detraction from the necessary rigidity in the plane of support.

It is assumed that the supporting structure includes no members which are

subject to compression and require to be stiffened. Such structures are known in the art of suspension-bridge-building. However, the lateral flexibility of such structures is not made use of in bridge-building because a bridge must always be stiff, so that two or more of such structures can be connected with one another by a stiff transverse connection. In the present instance lateral flexibility and movability of the whole system are not only harmless but even desiderata. If one were to construct such a towing installation with rigidity in transverse direction, there would be the danger that on lateral movements of the vessel, caused for instance by defective steering, a sudden straightening out of the traction rope would give rise to such immense lateral forces that either the track or the traction rope would be destroyed. Elastic deflection or diversion of these forces within the carrying plane is of the greatest importance for such installations.

In spite of the lateral flexibility such a structure will give the track hanging thereon so much stiffness in the vertical longitudinal plane that it is possible to construct it as a rigid continuous rail, which in every respect has all the advantages that are characteristic of a rigid track, as distinguished from chain- or cable-tracks. Particularly the sagging of the track, caused by the action of the moving load and found so very inconvenient, is eliminated.

The supporting structure is also of extreme cheapness, since transverse stays are dispensed with, and since there are in essence utilized only members which are subject to tensile stress, these members may be bars of circular cross-section.

Fig. 1 of the accompanying drawing is a longitudinal section of an installation according to the invention, and

Fig. 2 a plan.

Fig. 3 is a section drawn to the line A—B of Fig. 2 to a larger scale.

Fig. 4 is an elevation of one section of the installation.

Fig. 5 is a side view illustrating the suspension of the track together with a tug suspended from the track, and

Fig. 6 is a plan of means for compensating for changes in length caused by variations of temperature.

The tug or trolley *a* pulls itself by friction

along the track *b*, which in the construction shown by way of example consists of a rail of I-section, and in running along this rail tows or drags the vessel *c*. The track *b* is suspended from the supporting structure by suspension yokes *e*, which are preferably adapted to swing or oscillate pendulum fashion about the pivot or joint *g*, to prevent twisting movements between the tug and the rail, when the drift of the vessel is sideways, and to increase the lateral movability of the track by allowing additional oscillatory freedom. The bending and twisting stresses within the track that might be occasioned by the lateral oscillatory movements are generally speaking so slight that the provisions of special joints in the track or rail is not necessary. From the yokes is suspended also the electric conductor *L*, from which the current is fed to the tug by a sliding brush *F*, the distance between the tug and the conductor remaining uniform.

The section of the supporting structure shown in Fig. 4, which, as shown in Fig. 1, is hung from spaced posts or trestles *M*, *N*, *O*, etc., spanning the river or canal, consists of the upper ties *o*, the lower ties *u*, the main diagonals *d* and *t* crossing one another and subject only to tension, the verticals *v* subject to compression and the intermediate suspension bars *h*. All the bars which are subjected to tensile stress are preferably round steel bars, which offer less surface to wind and rust than other bars, stretch less and are considerably cheaper than cables or wire-ropes.

As is understood, the supporting structure may be of different shape and lacking members subject to compression. The construction shown has the advantage that it includes very few bars subject to compression, and moreover that there are no extra long tie bars, so that the structure can be built up at small cost.

In order to compensate for changes in length of the track due to fluctuations in temperature it is of advantage to incorporate in the track under the supporting point a member *b'*, which is elastic in a horizontal

plane, Fig. 6. At curved points of the water-way the compensation is effected solely by a change of the curvature *k* of the track, Fig. 2, which in its simplest form is effected by shortening the track relatively to the plan line of the upper tie. The curve requires no lateral staying or tensioning. At the same time in the track and in the lower tie a tensile stress whereby the structure is stiffened is set up in the same manner as by the above described elastic section of rail *b'*. This effect may be increased in the line of the track by additional tensioning means, for instance by the spring *m*, Fig. 4.

It is to be remarked that the invention is not only applicable for installations of towing ships, but can also be adopted with advantage in installations for conveyance of other vehicles or loads.

I claim:

1. A suspended track construction for the purposes indicated, comprising a track constructed of rigid rails and a suspension structure by which the track is suspended, said structure being stiff in a vertical plane to support said track against deflection, but laterally yieldable.

2. A construction according to claim 1, in which the suspension structure includes pendulous members free to oscillate laterally.

3. A construction according to claim 1, in which the suspension structure includes pendulous members free to oscillate laterally, and means on said members adapted to carry an electric conductor.

4. A construction according to claim 1, including an elastic member incorporated in the structure below the supporting point for compensating for changes in length of the suspension structure and track due to changes in temperature.

5. A construction according to claim 1, including a spring incorporated in a lower member thereof for continuously subjecting the suspension structure to tensile stress.

In testimony whereof I have signed my name to this specification.

ARTHUR HUGO MÜLLER.
